UNITED STATES PATENT OFFICE.

WILLIAM OWENS, OF DETROIT, MICHIGAN.

REVOLVING TABLE.

Application filed March 29, 1926. Serial No. 98,053.

My invention relates to a new and useful improvement in a revolving table in which the table may be revolved on its support so that a person sitting at the table may, by revolving the table, bring within easy reach the various articles positioned on the table.

I am aware that revolving tables of this class generally have been previously invented but the present invention has as its object the elimination of disadvantages inherent in the revolving tables referred to. Where the revolving tables are used for dining tables a rotation or revolving of the table while a person is dining thereon would remove from before the person the dishes and foods being used. In the present invention I have overcome this difficulty by providing a stationary portion upon which the viands and dishes to be used by the individual may be placed. These stationary parts I have shown spaced apart so that the structure of the table may be simplified and an economical arrangement provided. The provision of a table of this class as set out together with the various features of construction shown in the specification forms the object of the present invention.

The invention consists in the combination and arrangement of parts hereinafter described and claimed.

The invention will be best understood from a reference to the accompanying drawings which form a part of this specification and in which,

Fig. 1 is a side elevational view of the invention showing parts broken away and parts in section.

Fig. 2 is a top plan view of the invention.

Fig. 3 is a fragmentary sectional view taken on substantially line 3-3 of Fig. 1.

Fig. 4 is a fragmentary sectional view taken on substantially line 4-4 of Fig. 2.

Fig. 5 is a fragmentary sectional view taken on substantially line 5-5 of Fig. 2.

Fig. 6 is a sectional view taken on substantially line 6-6 of Fig. 3.

As shown in the drawings the invention comprises a preferably cylindrical support 7, secured to which are supporting legs 8, these supporting legs being formed from a strip of metal, the upper end of which is angularly turned to provide the supporting arms 9, the extreme end of which are further angularly turned to provide the

horizontally extending portions 10, mounted 55 upon which is a small table or support 11.

As shown in Fig. 1 and in Fig. 3 one of the supporting arms 9' is provided with an elongated longitudinally extending slot 12, through which is projected one end of 60 a support 13 having, at its projected end, a cross head 14, the arm 9' being bifurcated to provide the bifurcations 15 and 16 between which projects a lug 17 on the angularly turned portion 18 of the leg 8', the 65 lug 19 being pivotally connected to the bifurcations 15 and 16. The other end of the section 9' is provided with a tongue 9'' which is pivotally mounted between the bifurcations 20 and 21, which project from the 70 section 10' upon which is mounted the support 11'. The arm section 9' is provided, adjacent one end, with an elongated slot 22, through which projects a stud 23 secured to a keeper 24 which is provided at opposite 75 sides with the angularly turned fingers 25. The sections 11 are joined to adjacent sections 11 by means of pins 26 projected into sockets formed in the sections. Swingably mounted on one of the sections 11 is an arm 80 28 adapted to latch over a screw or bolt 29 inserted in the section 11'. The opposite end of the section 11' is provided with a loop forming bracket 30 in which engages a slideable bolt 31, slidably mounted on the support 11 by means of loop forming brackets 85 32 and 33, a suitable stud 34 serving as a gripping member for effecting a sliding of the bolt 31.

It is apparent that the bolt 31 and the keeper 24 serve to prevent a tilting of the support 11' when raised to the position shown in full lines in Fig. 1.

The construction is such that the support 11' may be lowered to the position shown in 95 dotted lines in Fig. 1, the arm 13 sliding to the upper end of the slot 12 to serve as a support. The keeper 24 is moved so that the stud 23 engages the forward end of the slot 22, the fingers 25 engaging opposite sides 100 of the free end of the section 10' so as to prevent swinging of the support 11' on the pivot with which it is connected to the arm section 9'. Thus it is clear that a portion of the table may be moved to a lower plane 105 and supported in the lower plane to accommodate juveniles.

Projecting upwardly from the supporting

- block 7 is a trunnion 35, which projects through a preferably cylindrical block 36, secured to the lower side of which, in the peripheral recess 37, is a wear plate 38 adapted to engage the roller bearings 39 which are positioned in the ring 40, said ring being positioned between the wear plate 38 and a wear plate 41 which is mounted upon a supporting block 7, in the peripheral recess 42.
- 10 Secured to the supporting block 36 by suitable L-shaped brackets 43 is a table top 44, projecting from the lower surface of which are a number of gripping members 45, whereby the table top 44 may be rotated on the trunnion 35 as a pivot so that a person sitting at one portion of the table, may by rotating the table top 44, bring within easy reach the articles placed on the table top.
- 15 Mounted on the trunnion 35 is a disc 46, which will serve as a support for a lamp, vase or the like, so that upon rotating the table top 44 the lamp or vase will not be rotated, it remaining stationary on the stationary disc 46.
- 20 25 From the description thus given it appears that I have provided a table which may be used for dining purposes and adapted for adjustment to accommodate children, permitting a portion of the supporting part of the table to be lowered to a lower plane.

30 It is also believed evident that the rotating center of the table will render its use highly efficient in that all of the contents of the table top are thus placed within easy reach of each individual so that the assistance of other individuals at the table will not be required by one individual to pass articles on the table. This feature of the table is believed particularly desirable in 35 restaurants and the like, where those eating at the table are strangers, the condiments and other common articles being placed on the rotating portion of the table.

40 45 While I have illustrated and described the preferred form of structure, I do not wish to limit myself to the precise form of struc-

ture shown, but desire to avail myself of such variations and modifications as come within the scope of the appended claims.

Having thus described my invention what 50 I claim as new and desire to secure by Letters Patent is:

1. In a table of the class described a supporting member; a table top mounted on said supporting member rotatably; an arm 55 projecting outwardly from said supporting member diagonally upwardly directed thereto, having an elongated slot formed therein intermediate its ends; a supporting member slidably mounted in said slot and adapted 60 for supporting said arm in horizontal position; a supporting surface; means for swingably mounting said supporting surface on the free end of said arm; a keeper slidably mounted on the free end of said arm for 65 engaging said swingable mounting means and preventing the swinging of said supporting surface relatively to said supporting arm, said keeper being operative only upon movement of said supporting surface into a 70 plane parallel with the plane of said supporting arm.

2. In a table of the class described, a supporting member; a table top rotatably mounted on said supporting member; a plurality of arcuate shelves extending around the periphery of said top and lying normally with their upper face flush with the upper surface of said table top and non-rotatable about said supporting member; a 75 diagonally extending arm projecting upwardly and outwardly from said supporting member; a brace mounted on said arm; means for swingably attaching one of said shelves to said arm; and means for locking 80 said shelf against swingable movement on said arm and for adjusting said arm to support said shelf in horizontal position below the plane of said table top.

In testimony whereof, I have signed the foregoing.

WILLIAM OWENS.
